FISH HOLDER

Proctor N. Carter, 930 Fairmont,
Jefferson City, Mo. 65101

Filed Jan. 8, 1973, Ser. No. 321,845

Term of patent 7 years

Int. Cl. D22—30

U.S. Cl. D22—30

FIG. 1

FIG. 2

FIG. 3

FIG. 4

FIG. 1 is a front elevation of a fish holder incorporating my design, the back elevation being identical to the front elevation.

FIG. 2 is a side elevation thereof, the opposite side being identical to the side elevation shown.

FIG. 3 is a top view thereof.

FIG. 4 is a bottom view thereof.

I claim:

The ornamental design for a fish holder, as shown and described.
